CLAIM

The ornamental design for a passive multiplexer, as shown and described.

DESCRIPTION

FIG. 1 is a perspective view of a passive multiplexer showing my new design;
FIG. 2 is a front view thereof;
FIG. 3 is a back view thereof;
FIG. 4 is a left side view thereof;
FIG. 5 is a right side view thereof;
FIG. 6 is a top view thereof; and,
FIG. 7 is a bottom view thereof.

(Continued)

The broken lines shown in the drawings are for the purpose of illustrating portions of the passive multiplexer that form no part of the claimed design.

1 Claim, 7 Drawing Sheets
